CLAIM

The ornamental design for a digital ultrasonic cleaner, as shown and described.

DESCRIPTION

FIG. 1 is a front view of the digital ultrasonic cleaner.

FIG. 2 is a rear view of the digital ultrasonic cleaner.

FIG. 3 is a left side view of the digital ultrasonic cleaner.

FIG. 4 is a right side view of the digital ultrasonic cleaner.

FIG. 5 is a top view of the digital ultrasonic cleaner.

FIG. 6 is a bottom view of the digital ultrasonic cleaner.

FIG. 7 is a front perspective view of the digital ultrasonic cleaner.

FIG. 8 is a rear perspective view of the digital ultrasonic cleaner.

FIG. 9 is an expanded view of an upper portion of the digital ultrasonic cleaner thereof; and,

FIG. 10 is an expended view of a lower portion of the digital ultrasonic cleaner thereof.

The broken lines in the drawings depict portions of the digital ultrasonic cleaner that form no part of the claimed design.
